(57) **CLAIM**

The ornamental design for an external SSD storage device, as shown and described.

DESCRIPTION

FIG. 1 is a perspective view illustrating my design with a cover portion at a first position.

FIG. 2 is a front view thereof.

FIG. 3 is a rear view thereof.

FIG. 4 is a left side view thereof.

FIG. 5 is a right side view thereof.

FIG. 6 is a top plan view thereof.

FIG. 7 is a bottom plan view thereof.

FIG. 8 is a perspective view illustrating my design with the cover portion at a second position.

FIG. 9 is a front view thereof.

FIG. 10 is a rear view thereof.

FIG. 11 is a left side view thereof.

FIG. 12 is a right side view thereof.

FIG. 13 is a top plan view thereof; and,

FIG. 14 is a bottom plan view thereof.

The features shown in broken lines form no part of the claimed design.
